UNITED STATES PATENT OFFICE.

FRED WILLIAMS AND LORENTS H. STENVIG, OF BELLINGHAM, WASHINGTON.

HORIZONTAL BAR.

1,410,149.

Specification of Letters Patent. Patented Mar. 21, 1922.

Application filed April 27, 1920. Serial No. 376,969.

To all whom it may concern:

Be it known that we, FRED WILLIAMS and LORENTS H. STENVIG, citizens of the United States, and residents of Bellingham, county 5 of Whatcom, and State of Washington, have invented certain new and useful Improvements in Horizontal Bars, of which the following is a specification.

This invention relates to supporting structure for horizontal bars, and has for its principal object to provide collapsible frame members which may be extended to functional position to hold and rigidly support a horizontal bar or the like, and which may 10 be folded together, or collapsed to release the bar and permit it to be packed or stored with the frame members in a minimum amount of space.

It is also an object of the invention to provide supporting frames of this character of 20 simple and durable construction which will substantially support a bar against lateral or longitudinal strain and yet have no fixed connection therewith; which allows quick 25 and easy disassembling of the parts.

In accomplishing these and other objects of the invention, we have provided the improved details of structure, the preferred forms of which are illustrated in the accompanying drawings, wherein:

Figure 1 is a perspective view of a set of bar supporting frames embodying the present invention in functional position.

Figure 2 is an end view of the same, showing in dotted lines, the manner of folding the legs together to release the bar, and showing extension members fixed to the legs.

Figure 3 is a view of a frame when in collapsed position.

Figure 4 is an enlarged detail view, illustrating a curved connecting bolt which secures the upper ends of the legs of a frame together.

Referring more in detail to the drawings:

1 designates a horizontal bar or the like, which is supported at its opposite ends by means of frame structures 2 embodying the present invention. Each of these frames comprises two legs, 3, which are spaced apart at their lower ends and at their upper ends have faces 4 cut on a bevel thereto, which are brought together in a vertical joint; thus forming an inverted V-shaped frame.

5 The opposed faces 4 of the legs 3 are each provided with seats, or notches, 5, which as

shown in Figures 1, 2 and 3, are semi-circular and register with each other so that, when the legs are brought together they will act co-operatively to grip and seat the end of a bar 1 therein.

Radially curved bolts 7 extend slidably through apertures 8, adapted thereto at points a little below the upper ends of the legs. These bolts are provided with heads 65 9 at one end and have nuts 10 threaded onto their opposite ends which may be adjusted to adapt the gripping or rod-supporting ends to various sizes of rods. The slideable mounting of the bolts also permits folding of the 70 legs together, as is shown in Figure 3.

At their lower ends, the legs are spaced apart and braced by a pair of hingedly connected bars 12 and 13, which, at their outer ends, are also hingedly connected to the 75 legs. This particular manner of bracing limits the spread of the legs, normally prevents them from being moved together, but permits folding of the paired bars together, on moving their hingedly connected ends 80 upwardly, so that the legs may be moved together and thereby release the bar from the notches at their upper ends.

It is also desired that the notches 5 extend across the faces 4 in a manner that when the 85 bar 1 is seated it will cause the frames to be inclined toward each other at their upper ends and will thus brace the bar against longitudinal movement. It is also desired 90 to provide the base of each leg with a shoe or pad of rubber, or the like, 20, which will prevent slipping.

In Figure 2 we have illustrated the attachment of extension legs 15 to the legs 3. 95 This is done by extending the lower ends of the legs 15 through loops formed by bands 16, fixed to the lower ends of the legs 3 and securing their upper ends to the legs 3 by bolts 17, which may be extended through registering apertures 18 in the legs.

In Figure 4 we have illustrated the mounting of a square bar in the supporting frame. In this construction the notches 5 are cut square instead of semi-circular notches, and may be made to correspond to the character 105 of the bar used, and may be semi-circular, square, semi-hexagonal, or any other necessary or desired shape to fit correspondingly shaped ends of the bars supported.

In using frames of this character, it is 110 only necessary to place the end of a bar within the notches 5, and to spread the legs

apart, as in Figure 2, to draw the upper ends of the legs tightly against the opposite sides of the bar end. The tension with which the legs grip the bar ends may be adjusted by adjustment of the nuts at the ends of the bolts.

To release the bar, it is only necessary to break the brace members 12 and 13 upwardly, as shown in dotted lines in Figure 2, which permits the upper ends of the legs to spread apart from the bar.

It is apparent that such a device would be substantially, rigid, and easily handled and could be collapsed and stored in a small and compact bundle.

What we claim as new, is:

The combination with a horizontal bar of frames for supporting said bar at its opposite ends, each of said frames comprising a pair of diverging legs cut on a bevel at their

upper ends and adapted to be fitted together in a vertical joint, the beveled portions having notches cut therein to cooperatively receive and support an end of the bar therein, a bolt curved radially about the bar and functionally connecting the legs at points below the upper ends and having an adjustable nut at one end thereof and extending slidably through apertures in the legs, and collapsible brace members connecting the lower ends of the legs adapted to be extended to spread the legs apart to force them together at their upper ends to grip the bar and to be folded together to permit the upper ends to release the bar.

Signed at Bellingham, Whatcom County, Washington, this 14th day of April, 1920.

FRED WILLIAMS.
LORENTS H. STENVIG.
